UNITED STATES PATENT OFFICE.

JOHN W. THURLOW, OF OSCEOLA, IOWA.

HORSE-FOOT PROTECTOR.

SPECIFICATION forming part of Letters Patent No. 591,510, dated October 12, 1897.

Application filed March 1, 1897. Serial No. 625,505. (No model.)

To all whom it may concern:

Be it known that I, JOHN W. THURLOW, a citizen of the United States, residing at Osceola, in the county of Clarke and State of Iowa, have invented a new and useful Horse-Foot Protector, of which the following is a specification.

My object is to prevent the dangers and accidents incident to horses getting their feet over a fence-wire and cutting and lacerating the flesh and tendons and crippling, lamening, and destroying their value.

It is a common occurrence where horses, especially colts, are in adjoining pastures that are separated by wire fences, plain or barbed, they get their heads together over the fence and paw with their front legs in play or to make a breach in the fence and get a foot fast on a wire in such a manner that the wire will be confined between the horny sheath of the hoof and the fetlock, and in their efforts to get free the wire will cut into the flesh and tendons and practically ruin the foot and the animal.

My invention consists in the armor device adapted to be detachably fastened to a horse's foot, as hereinafter set forth, pointed out in my claims, and illustrated in the accompanying drawings, in which—

Figure 1 is a perspective view showing the invention applied to a horse's foot as required for practical use. Fig. 2 is a perspective view of the complete device in an open position and ready to be applied. Fig. 3 is a diagrammatic view of one of the skeleton metal armor-pieces used in the construction of the complete device.

The letters A and B designate two mating skeletons or frames that are preferably cut from sheet-metal plates by means of suitable dies and a press. They vary in size as required to produce protectors for animals that vary in age and size. Before applying them to a flexible band adapted to be fastened around the foot they are bent and bowed outward and then riveted to the outside surface of a band C, that is preferably made of leather. This flexible band may be complete in one piece or composed of a number of pieces riveted together by the same rivets used for fixing the skeleton metal armor-pieces A and B thereto.

The leather may be in two pieces of skeleton form corresponding with the metal pieces, and a connecting-piece of leather, D, placed between their inner ends to be overlaid by the leather pieces on the inside and by the metal pieces on the outside, as shown in Fig. 2. By thus fixing the rigid metal pieces of armor to the flexible band a hinged connection is produced between the two metal pieces and a joint that allows the complete device to be opened and closed, as required to be put on and off a horse's foot.

Buckles fixed to one end of the flexible band C and straps integral with or fixed to the other end adapt the device to be readily fastened and unfastened.

In practical use when the protector is applied to a horse's foot, as shown in Fig. 1, and the foot is thrown over a fence-wire and the horse makes effort to free his foot the metal armor will prevent the wire from coming in contact with the skin and flesh and will resist the force of the wire and the pressure of the animal will cause flexion in the wire and allow the foot to slip off from the wire and thus save the foot from being cut and the animal damaged or ruined.

I claim as my invention—

1. A foot-protector for horses, comprising a flexible band adapted to be fastened around a foot, and pieces of metal armor fixed on the outside surface of the band, and fastening devices on the ends of the flexible band.

2. A foot-protector for horses consisting of mating curved skeleton metal armor-pieces fixed to a flexible band to produce a hinge-joint between them and fastening devices on the ends of the flexible band for detachably connecting the ends.

3. The armor-pieces A and B, a flexible band consisting of two mating parts corresponding in form with the said armor-pieces and a flexible piece D fixed to the inner ends of the mating parts of the band to produce a hinge-joint between the two end portions and straps and buckles on the free ends of the band, arranged and combined as and for the purposes stated.

JOHN W. THURLOW.
